PREPARATION OF STOCKINGS FOR
MARKETING

Andrew E. Vaughan and Andrew E. Vaughan, Jr.,
Pottstown, Pa., assignors to The Vaughan Knit-
ting Company, Pottstown, Pa., a corporation of
Pennsylvania

Application August 5, 1939, Serial No. 288,592

11 Claims.

(Cl. 223—76)

This invention relates to the preparation of stockings for marketing, and it is concerned not only with the prepared articles, but also with the method of preparation and with apparatus or devices designed for the carrying out of the method.

Ordinarily stockings are pressed flat in the plane of their front and rear longitudinals to show their side profiles, and marked for size according to foot length. From a stocking prepared in this way, it is impossible for the purchaser to get any idea as to the exact plan area and shape of the stocking foot, and the selection of the proper size other than by number is consequently made difficult. This is particularly true in connection with infant's hosiery where the selection of stockings or socks of adequate foot size is of prime importance.

Our invention has for its chief aim to overcome the above drawbacks, which objective we realize in practice as hereinafter more fully disclosed, by flat pressing the leg and the foot respectively in the planes of their side longitudinals, with incidental indentation of the fabric at opposite sides of the angle, and thereafter folding the leg about a line crosswise of the ankle, down upon the foot. Thus, for example, in an infant's sock prepared for marketing according to our invention, the full plan area of the foot is shown at one side of the package, and the transverse width of the leg at the other side, so that selection for correct size may be made with the utmost facility.

Another object of our invention is to provide a simple device or apparatus suitable for the practice of the new method. As also more fully disclosed in detail hereinafter, the means devised for this purpose includes a suitably heated mounting form component over which the stocking or sock is stretched, said component having a transversely flattened leg portion joined to a transversely-flattened foot portion in a vertical plane somewhat inward of the heel end of the foot; and a presser component including pad block elements which are configured to correspond with depressions in opposite sides of the ankle portion of the mounting form component, and which by coaction with said depressions predetermine the production of inward "accordion" folds at the ankle regions of the stocking or sock.

Other objects and attendant advantages will appear from the following detailed description of the accompanying drawings, wherein Fig. I is a perspective view of an infant's stocking or sock

5 pressed in accordance with our invention, and ready for folding.

Figs. II and III show the opposite sides of the pressed article after folding.

Fig. IV is a view in side elevation of a stocking-shaping device suitable for carrying out our new method.

Fig. V is a fragmentary longitudinal sectional view of the device.

Fig. VI is a horizontal section viewed as indicated by the angled arrows VI—VI in Figs. IV and V.

Fig. VII is a fragmentary cross section taken as indicated by the arrows VII—VII in Figs. IV and V; and

Fig. VIII is a fragmentary perspective view of the mounting form component of the device.

In accordance with our invention, a stocking or sock S is prepared for marketing after the manner illustrated in Fig. I of the drawings, that is to say, the foot F and the leg L are pressed flat respectively in the planes of their side longitudinals, with incidental indentation of the fabric at opposite sides at the region of ankle juncture as at B, the indentations being so proportioned and configured as to define inwardly-collapsing accordion folds as shown. After pressing of the stocking or sock S as explained, the leg L is folded along a transverse line M extending crosswise of the instep, down upon the foot F. From this procedure results a neat, flat and compact package in which, see Figs. II and III, the exact shape and plan area of the foot F is exposed to view at one side or face, and the full transverse area of the leg L at the other. With stockings or socks S so prepared, it will be evident that no difficulty whatever will be experienced by the purchaser in selecting for proper foot size especially when the size number is not known by the purchaser. It will, moreover, be evident that stockings or socks S so prepared can be readily stacked or piled in lots of half dozens or dozens, and packed for the market in boxes of small size as compared with those required for hosiery pressed in the ordinary way.

The apparatus which we have devised for the practice of our improved stocking pressing method consists of two components, to wit: a mounting form component which is comprehensively designated by the numeral 1 in Figs. IV—VIII, and a presser component which is similarly designated by the numeral 2. As shown, the mounting form component 1 has a leg portion 3 of flat shape-edged cross section arranged transversely of, and connecting integrally through an

ankle portion 4 with a flat horizontal sharp edged foot portion 5 in a vertical plane somewhat inward of the heel end of said foot portion. The ankle portion 4 flares upwardly toward the foot, that is to say, it has flat diverging front and rear faces 6 and 7 at an acute angle to each other which merge into the foot portion 5 as clearly shown in Figs. IV, V and VIII. It will, also, be noted from Fig. V that the side edges of the front face 6 of the ankle portion converge toward the foot portion 5. In the opposite sides of its ankle portion 4, the mounting form component 1 has depressions 8 defined by meeting plane surfaces 9, 10, 11 which extend angularly inward respectively from the corresponding sides of the foot portion 5 and the front and rear faces 6 and 7 of said ankle portion, the front or instep surface 6 being provided with a crosswise-extending scoring groove 12. The mounting form component 1 is constructed hollow throughout as shown in Figs. V and VII so that it may be heated from within by circulation of steam through it, or by an electric heating unit inserted within it after common practice in the art.

The presser component 2 of the shaping device includes a pair of pad-block elements 13 of which the inner sides are configured to accurately fit the depressions 8 at opposite sides of the mounting form component 1, as shown in Figs. VI and VII. In the illustrated instance, the blocks 13 are integrally formed with a pair of manipulating handles 14 which are interpivoted at 15 and influenced by a relatively strong compression spring 16 which tends to maintain said blocks yieldingly but firmly engaged within the depressions 8 of the mounting form component 1. Extending crosswise between the forward extensions 17 of the manipulating handles 14 is a scoring member 18 in the form of a helical tension spring whereof the ends are engaged with anchorage studs 19. With the parts assembled as shown in Figs. V and VI, the spring 18 registers with the scoring groove 12 of the mounting form component 1.

In the use of the shaping device, the stocking or sock S is drawn over the heated mounting form component 1 as shown in Fig. V. The presser component 2 is then applied as shown in Figs. VI and VII with its pad blocks 13 pressing the stocking fabric inward at the sides into the depressions 8 and the scoring member 18 displacing the instep fabric inward slightly at the scoring groove 12. Under the action of the heat, the stocking or sock S is dried and shaped to the configuration of the mounting form component 1, and, when removed, appears as shown in Fig. I with its foot and leg portions F and L perfectly flat and at right angles, with the inward accordion folds B at the region of the juncture of the foot F and the leg L, and with a transverse scoring line M crosswise above the instep about which the leg L is subsequently folded down flat upon the foot F as previously explained.

Having thus described our invention, we claim:

1. A stocking shaping device comprising a mounting form component with a foot portion, a leg portion and an ankle portion connecting with the foot portion intermediate the ends of the latter over which the stocking is drawn, said ankle portion having depressions in the opposite sides defined by plural lines which intersect at

a common point; and a presser component including oppositely influenced block elements configured to fit the depressions in the mounting form component.

5 2. A stocking shaping device comprising a mounting form component with a foot portion, a leg portion and a connecting ankle portion, over which the stocking is drawn, and with depressions in opposite sides of its ankle portion; and a presser component including a pair of pad block elements which are configured to fit the depressions at opposite sides of the mounting form component, and yielding means for pressing the pad block elements into said depressions.

15 3. A stocking shaping device according to claim 2, in which the mounting form component is heated.

20 4. A stocking shaping device according to claim 2, in which the mounting form component is hollow for capacity to be heated from within.

25 5. A stocking shaping device according to claim 2, in which the pad block elements of the presser component are carried by an interpivoted grasp handle, and wherein the yielding means consists of a spring which is influential upon said handles.

6. A stocking shaping device according to claim 2, in which each of the depressions at opposite sides of the mounting form component is defined by three meeting plane surfaces.

30 7. A stocking form according to claim 2, in which the front and rear faces of the ankle portion of the mounting form component are flat and diverge in merging with the foot portion, and in which each of the side depressions is defined by meeting plane surfaces which extend inwardly at an angle respectively from the corresponding side edge of the foot and from the side edges of the front and rear surfaces of the ankle portion.

35 8. A stocking shaping device according to claim 2, in which a groove extends crosswise of the front of the ankle portion of the mounting form component; and in which is positioned an extensible member extending crosswise between the pad block elements of the presser component to produce a fold crease crosswise of the ankle portion of the stocking.

40 9. A hosiery shaping form with a leg portion of substantially flat and hollow cross section arranged transversely of and connecting, through a widening ankle portion, with a foot portion of similar cross-section, and depressions in the opposite sides of said ankle portion.

45 10. A hosiery shaping form according to claim 9, in which the front and rear surfaces of the ankle portion are flat, and in which a scoring groove extends crosswise of the front of the ankle portion.

50 11. A hosiery shaping form according to claim 9, in which the front and rear surfaces of the ankle portion are flat, in which each of the side depressions is defined by meeting plane surfaces which extend inwardly at an angle respectively from the corresponding side edge of the foot portion and the corresponding side edges of the front and rear surfaces of the ankle portion, and a scoring groove extends crosswise of the front of the ankle portion.
